UNITED STATES PATENT OFFICE.

WILLIAM OLIVER, OF LOCKPORT, NEW YORK, ASSIGNOR TO OLIVER BROTHERS, OF SAME PLACE.

DESIGN FOR A BICYCLE-STAND.

SPECIFICATION forming part of Design No. 27,768, dated October 19, 1897.

Application filed July 6, 1897. Serial No. 643,661. Term of patent 7 years.

To all whom it may concern:

Be it known that I, WILLIAM OLIVER, a citizen of the United States, residing at Lockport, in the county of Niagara and State of New York, have invented and produced a new and original Design for Bicycle-Stands, of which the following is a specification, reference being had to the accompanying drawing, forming a part thereof.

10 This design relates to the configuration of a bicycle-stand, the accompanying drawing being a perspective view of a bicycle-stand embodying my design.

15 The distinctive feature of my design consists in the peculiar shape of the upright or holding portion of the stand.

Referring to the drawing, A represents the base-frame, consisting of four bars *a*, four supporting-feet *b* at the corners thereof, and 20 two pedestals *c*, arranged centrally on two opposite bars *a*.

The frame of the upright or supporting por-

tion of the stand consists of two standards *D* *D*, which rise from the pedestals, an upper horizontal cross-bar *d*, connected at its ends 25 by curved portions *d'* with the upper ends of the standards, and a lower horizontal cross-bar *d*², connected at its ends with the lower portions of the standards by rosettes *d*³.

E represents a number of upright bars which 30 are preferably arranged in pairs to form loops or racks, each bar being connected at its ends by a rosette *e* with the adjacent cross-bar. The rosettes at the adjacent ends of each pair of upright rods may be connected by a connecting-piece *e'*.

I claim as my invention—

The design for a bicycle-stand, substantially as herein shown and described.

Witness my hand this 2d day of July, 1897. 40

WILLIAM OLIVER.
